UNITED STATES PATENT OFFICE

2,512,935

POCKET DENTURE BRUSH

Hazel B. Hansen, Glendale, Calif.

Application November 13, 1947, Serial No. 785,598

3 Claims. (Cl. 132—84)

1

My invention relates to dental appliances and especially relates to an article intended to be used by the wearers of dentures, and is particularly designed to be sufficiently small and inconspicuous so as to be carried in a woman's purse or in a man's pocket.

The article, while primarily designed for the wearers of dentures, may of course also be used by persons who are more comfortable, if after eating, they are able to clean food from between irregularly spaced or crowded natural teeth or from under dental bridges.

Persons having to wear dental plates or dentures are very often inconvenienced and subjected to discomfiture by particles of food lodging between the denture and the gums or roof of lower portion of the mouth, thereby causing discomfort as well as impairing the fit of the plates; and an object of my invention is to provide a novel article which will enable such persons to immediately and inconspicuously remove any foreign particles that may cause such discomfiture, without the embarrassment of having to carry with them a number of special brushes, tubes of paste and the like.

Another object of my invention is to provide a novel tooth and/or denture cleaning set which in addition to a tooth-cleaning brush, may if desired carry a supply of dentifrice or cleaning material, instead of a denture powder.

A further object of my invention is to provide a novel article of the kind described which is provided in addition to a brush and a supply of cleansing material, may also carry an additional supply of material such as a supply of make-up paste or lip stick.

Another object of my invention is to provide a novel article of the kind described in which the interfitting parts are arranged so as to be fitted together and taken apart with a maximum of ease, and which when in carrying position will be compact and easily carried in a lady's handbag or purse or in a man's pocket without being conspicuous.

The invention comprises the parts and combination of parts and arrangement and assembly thereof as will more particularly hereinafter appear from the description thereof and as pointed out in the claims.

Other objects, advantages and features of the invention may appear from the accompanying drawing, the subjoined detail description and the appended claims.

The accompanying drawing illustrates the invention in a form I at present deem preferable.

2

Figure 1 is a view in side elevation of a pocket denture brush constructed in accordance with my invention, and being shown fitted together in collapsed position for carrying purposes.

Fig. 2 is a view in side elevation of the article arranged for use, such as for example, as a tooth brush.

Fig. 3 is a view partly in plan and partly in section; and taken on irregular line 3—3, Fig. 2; but showing the parts detached or separated from each other, to more clearly illustrate the construction thereof, and the relative association of parts, one with the other. Some parts are also turned to more clearly illustrate the cooperative connecting elements of associated members.

Fig. 4 is a cross sectional view on line 4—4, Fig. 1, looking in the direction of the arrows.

In the drawing the numeral 10 indicates a hollow handle or case. In the form of the invention shown the handle or case 10 is formed with a closed end 10' and with bayonet slots 12, formed in the wall of the case toward its open end. Holes 13, 13' are provided in the handle 10 for ventilation purposes. A brush 14 is provided with a back 14a preferably of curved form and bristles 14b are arranged in spaced tufts of varying length, and extend therefrom, but obviously however, the form of the brush back and arrangement of the bristles may be varied as 30 may be found expedient.

The back of the brush 14 is fitted into a base 16 having an outside diameter less than the inside diameter of the handle or case 10 and is provided with projecting pins 18 adapted to fit into the bayonet slots 12 in the handle 10 so that the brush may be secured in nested condition in the handle 10 (Fig. 1), or with the brush projecting outwardly from the handle for use, as shown in Fig. 2.

I utilize the brush base 16 to constitute part of a receptacle 20 for a denture powder or a cleansing material such as a tooth powder or dentifrice and preferably though not necessarily I provide an additional part 22 to complete the receptacle

part 20 and brush base 16, and these are provided with parts by which they may be easily and quickly secured together, and the part 22 is preferably secured to the handle 10 if desired, through an intermediate member 28 for reasons 50 hereafter explained, although the base 16 and part 22 may be directly connected to the handle 10.

The chamber or receptacle 20 is preferably formed in the part 22, that is provided with a 55 threaded end 24 adapted to be screwed into a

threaded axial bore 26 formed in the brush base 16.

It is advantageous to provide a receptacle for material often used to aid the wearer in make-up, such as lip stick after use of an article of this character, and for this purpose I provide a container 28 provided with means by which it may be connected both to the part 22 and the handle 10. As clearly shown in Fig. 3 the container 28 is formed as a tubular member having a closed end and two pairs of pins 30 and 32, adapted to respectively engage in a pair of bayonet slots 34 and 12, and which are respectively formed in the wall of an axial recess 36 provided in the base of part 22, and in the handle 10. The interior of container 28 may be filled with paste, adhesive material, as for example, lip stick of the wearer's desired shade, which the user may touch up her lips with, after brushing the teeth or denture plates.

It will be seen from the foregoing that I have provided a simple, inexpensive and compact article for use as a denture brush, and which may be easily and quickly assembled into position for use or for carrying the same in compact form in a purse or pocket; and whereby a person who has false teeth or dentures may clean the same after eating and apply denture powder, or brush the teeth after eating, and which operation will not be conspicuous to others. That is to say, my invention may be carried in a person's purse or pocket without detection, and enable such person to easily and quickly clean the teeth or dentures and apply denture powder while in a bath or rest room without associates or friends knowing that such an operation is being performed.

I claim:

1. A dental appliance including: a tubular handle; a base member; brush means secured in said base member; interfitting means carried by said base and said tubular handle effective to secure said brush means in nested position in the handle and projecting therefrom for use; a member detachably secured to said base member and having a diameter equal to that of the handle, and provided with a recess in one end; a container having an outside diameter smaller than the inside diameter of the handle and adapted to be detachably secured in said recess and to project therefrom; and interfitting means on the projecting end of said container engaging with the interfitting means on the handle whereby when the brush is arranged to project from the handle for use, the container member is effective to secure the base member and member detachably secured thereto to said handle member.

2. A pocket denture brush containing a hollow handle member, closed at one end and open at its other end; a base member having brush means extending therefrom, and adapted to be received in said handle member; a receptacle member detachably connected to said base members, and provided with receptacle chambers at each end; a cup-shaped intermediate members received in one of said receptacle chambers and adapted to be received in said handle member; means on said receptacle member and cup-shaped member coacting to secure said members to each other so as to close the open end of said cup-shaped member; other means on said cup-shaped member and said handle member coacting to secure said base member and handle member when said brush means is inserted in said handle member.

3. A pocket denture brush comprising a tubular handle member, having an open end; a base member having brush means connected thereto; a part member having a reduced portion extending therefrom adapted to be detachably connected to said base member, and provided with a chamber extending through said reduced portion and into said part, and being closed when connected to said base member; said part member also being provided with another chamber at its end opposite said first mentioned chamber; a cup shaped member adapted to fit into said other chamber; means to secure said cup shaped member to said part member and when engaged to close the open end of said cup shaped member; coacting means on said base members and the exterior of said handle member to secure said brush means in nested position within the handle; and means on said cup member coacting with means on said handle member to secure said brush means in projected position from the handle.
